UNITED STATES PATENT OFFICE.

JACOB A. HARMAN, OF PEORIA, ILLINOIS.

DERRICK OR EXCAVATING-MACHINE.

1,385,543.

Specification of Letters Patent. Patented July 26, 1921.

Application filed September 12, 1919. Serial No. 323,330.

To all whom it may concern:

Be it known that I, JACOB A. HARMAN, a citizen of the United States, a resident of Peoria, in the county of Peoria and State 5 of Illinois, have invented new and useful Improvements in Derricks or Excavating-Machines, of which the following is a specification.

This invention has reference to derricks 10 or excavators, and relates particularly to that type mounted on a traveling frame or platform and intended to be used in excavating and moving earth or other material, such as in the construction or cleaning out 15 of drainage ditches and the construction of railroad, levee or other embankments.

In the use of derricks of the type referred to, it is necessary from time to time to clean out or deepen agricultural drainage ditches, 20 and so far as I am aware, there is no satisfactory and economical method of supporting and moving forwardly along such ditches, the machines which are used therefor.

25 One of the common methods employed for this work, is to place a steam shovel or a drag line type of dredge, centrally located, upon beams long enough to span the ditch, and rest upon wheels or rollers. Few of 30 these ditches are less than thirty feet wide and many of them are fifty or more feet wide on top, so that the structure necessary to carry the dredging machinery, located and working over the center of the ditch, 35 is necessarily very heavy and expensive to provide and operate. All excavators of this type of which I have any knowledge have a revolving derrick or swinging boom, centrally located, with reference to the span 40 or width of the traveling platform upon which it is placed; in all such cases the size or strength of the beam of the platform must be at a maximum, because the load is centrally placed between the supports.

45 My invention has for its principal object, to place the revolving or swinging portion of the derrick or excavator nearer to one of the supports than the other, and it will usually be placed only a short distance from 50 the center line of one of the end supports, so that the strength of the beams carrying the load between the two supports will be practically at a minimum; thus very greatly reducing the required strength of the beams, 55 the cost of construction and the cost of moving the equipment as the work progresses.

A further object of the invention is to provide a three point suspension for the derrick or excavator.

A further object of the invention is to 60 provide supporting beams for the derrick, which span the ditch, of a character which will allow one end of the frame to be higher than the other, while at the same time the hoist house and equipment controlling the 65 boom and bucket may remain level.

And a still further object of the invention is to provide a supporting beam or frame which is extensible, whereby to adapt the 70 frame to different width ditches.

That the invention may be more fully understood, reference is had to the accompanying drawings, forming a part of the description, in which:

Figure 1 is a side elevation of a derrick 75 or excavator embodying my invention, the same shown when at work cleaning out or deepening a drainage ditch;

Fig. 2 is a view similar to Fig. 1, except that the supporting beam or frame is shown 80 constructed in a manner which will allow one end to be at a higher point than the other;

Fig. 3 is a view, also similar to Fig. 1, except that it shows the supporting beam 85 or frame constructed so that it may be extended to adapt it to ditches of different widths, and

Fig. 4 is a plan view of the derrick or excavator, illustrating the three point sus- 90 pension;

Fig. 5 shows a conventional form of caterpillar for the truck, applied to the truck supporting the hoist house, and

Fig. 6 is an elevation of the structure 95 shown in Fig. 5, the caterpillar shown on the berm surfaces, displacing the track and wheels shown in the preceding figures.

Like characters of reference denote corresponding parts throughout the figures. 100

As showing the application and use of the derrick or excavator, I have illustrated by cross-section and in plan, a ditch A banked by the berm surfaces B.

On each of the berm surfaces are laid the 105 ties C and the rails D.

The derrick or excavating equipment proper is not unlike that now in common use, *i. e.* comprising the usual hoist-house 1, mounted to revolve on the usual and well known bull-wheel or turn-table 2. Connected with the hoist-house, that its outer end

may be raised and lowered, is the boom 3. The cables 4 are provided for this purpose. 5 denotes the excavating bucket to which is connected a cable 6, whereby it may be controlled at suitable points, and 7 is the cable controlling the loading and trip of said bucket.

The supporting frame for the derrick or excavator, comprises preferably the cross-beam 8, Fig. 1, or the cross-beams 8 and 9, Figs. 2, 3 and 4. In Fig. 1, the beam 8 is a single beam adapted to span a given width ditch. In Figs. 2, 3 and 4, the beams 8 and 9 make it possible, as will be explained, to adapt the opposite ends of the beams to different levels and to extend the supporting frame so as to adapt the same to different width ditches.

In Fig. 2, the forward extension 9 of the beam 8 has its forward end raised at an elevation above the forward end of the beam 8. This may be accomplished in several different ways, but as a simple and inexpensive expedient, the rear end of the beam 9 may be bolted at 10 to beam 8, inclined forwardly and supported in this position by the upright 11, bolted to the end of the beam 8 and the body of the beam 9.

In Fig. 3, the beams 8 and 9 are shown constructed in a manner allowing the beams 9 to be extended to a position to adapt the supporting frame to different width ditches. This may be accomplished in several different ways, but as a simple and inexpensive expedient, the two beams may be provided with a plurality of corresponding bolt holes to receive bolts 12. The full and dotted lines illustrate the different positions to which the frame may be adjusted.

40 The outer ends of the beam or beams 8 and 9 are preferably connected to and supported by the short truck 13, having wheels 14 traveling on the rail D. This constitutes one of the points of suspension for the derrick or excavator.

45 The inner ends of the beam or beams 8 and 9 are preferably connected to one end of a truck 15, substantially longer than the opposite truck 13, for reasons which will become apparent. This truck also has wheels 16 traveling on the rail D. Connecting the forward end of the truck 15 and the beam 8 intermediate its length, is the angularly disposed bracing and supporting beam 17. 50 The end of the truck 15 to which the beam 8 is connected, constitutes the second point of suspension, and its forward end to which the brace 17 is connected, constitutes the third point of suspension.

60 In Figs. 5 and 6, I have shown a conventional form of a caterpillar movable upon the berm surfaces of the ditch to take the place of the track and wheels previously referred to. This caterpillar is referred to 65 generally as 17, and while I have only shown

the caterpillar in Fig. 5 as applied to the truck 15, supporting the hoist house, it is understood that a similar traction means would be used on the truck 13.

Returning now to the derrick or excavator proper, it will be observed that I have mounted the revolving portion of the derrick, or excavator, nearer to the support 15 than to the support 13. In other words, off-center, or eccentric to the span or width of the traveling platform on which it is placed. I prefer that the revolving portion of the derrick or excavator should be placed only a short distance from the center line of the support 15, so that the strength of the beams carrying the load between the two supports 13 and 15, will be practically at a minimum.

My invention will permit the use of existing type of excavating machinery, and the machine will have the further advantage of being able to dig or clean out a very much wider ditch, and deposit the excavated material at a greater distance from the ditch bank (see dotted line position of bucket, Fig. 1) because the revolving portion of the machine may be so located upon the traveling frame that it will be over the edge of the ditch and can move the material the distance of the swing of the boom; or, when cleaning out an old ditch, can readily place the excavated material back of the spoil-bank of the original excavation, as already pointed out.

What I claim is:

1. In a derrick or excavator, in combination, a pair of wheel supports, one longer than the other to provide a three point suspension frame, a span for a ditch, comprising a beam connected to the short wheel support and one end of said longer wheel support, bracing and supporting means for said beam, and a revolving derrick mounted on said span, off center or eccentric to the width thereof, and at a short distance from the center line of one of said supports.

2. In a derrick or excavator, in combination, a pair of supports, an extensible platform connecting said supports to provide an adjustable span for different width ditches, and a revolving derrick mounted on said platform, off-center or eccentric to the width of the platform, and at a short distance from the center line of one of said supports.

3. In a derrick or excavator, a pair of wheel mounted supports adapted to travel on the berm surfaces of a ditch, a platform to span the ditch and connected to travel with said supports, a turn-table having a fixed location on said platform eccentric to the width thereof, and a short distance from the center line of one of said supports, and a derrick revolvably mounted on said turn-table.

4. In a derrick or excavator, in combination, a pair of supports, traction means connected with said supports to move on the berm surfaces of a ditch, a platform connecting said supports and designed to span a ditch, and a revolving derrick mounted on said platform, off-center or eccentric to the

width of the platform, and at a short distance from the center line of one of said supports.

In witness whereof, I have hereunto affixed my hand this 5th day of September, 1919.

JACOB A. HARMAN.
